UNITED STATES PATENT OFFICE.

RALPH H. NORTON AND CHESTER M. MACKENZIE, OF CHICAGO, ILLINOIS, ASSIGNEES
TO ACME STEEL GOODS COMPANY, OF CHICAGO, ILLINOIS, A CORPORATION OF
ILLINOIS.

STRAP-STRETCHER.

1,242,026.

Specification of Letters Patent. Patented Oct. 2, 1917.

Application filed April 13, 1917. Serial No. 161,861.

To all whom it may concern:

Be it known that we, RALPH H. NORTON and CHESTER M. MACKENZIE, citizens of the United States, residing at Chicago, in the county of Cook and State of Illinois, have invented certain new and useful Improvements in Strap-Stretchers, of which the following is a specification.

The present invention relates to tools such as used in stretching steel bands or straps around packing boxes and the like. The object is to provide a tool which can be used with sureness and despatch,—one in which the strap ends to be united may be readily received and one which is capable of gripping the strap, and powerfully stretching and tightening the same without any slippage, and holding the overlapped ends securely while they are being united or sealed. The present invention also provides for quickly releasing the tool by a simple maneuver and restoring it to condition for operating upon another strap. Other desirable objects attained by the present invention are economy in production due to simple and manufacturable character of the component parts and ease with which they can be assembled; and lightness of construction without sacrifice of strength or durability.

In the drawings which accompany and form part of this specification Figure 1 shows a complete tool in top plan view, with end portions of a strap ready to be stretched; Fig. 2 shows the tool in side elevation and the strap end portions in edge view, all in the same state of preparedness depicted in Fig. 1, and with one portion of the tool in section; Fig. 3 is a vertical section on the line 3—3 of Fig. 1; Fig. 4 is a similar sectional view but illustrates the opposite condition or the release condition after the strap has been stretched and sealed, and the end portions of the strap are therefore shown with the seal applied; Fig. 5 is a cross section on the line 5—5 of Fig. 1; Figs. 6 and 7 are similar sectional views on an enlarged scale illustrating the action of one of the gripping devices; and Fig. 8 is a bottom view of one of these devices.

The reference numeral 2 designates the base of the tool which is an L-shaped piece of metal formed or provided with a rack 2^a running lengthwise along the middle portion

of the top of its longer leg. This leg of the L-shaped base is T-shaped in cross section, as clearly shown in Fig. 5 for the purpose of constituting the most desirable character of slideway for a metal slide block 3. The latter is channelled to fit the said slideway and also to bridge the rack, as also clearly shown in Fig. 5. The central upper portion of this slide block is open to accommodate a gear wheel 4 in mesh with the rack, said gear wheel being trunnioned in ears formed upon the slide block. About the axis 4^a of this gear wheel is pivoted an operating lever 5 which is bifurcated to straddle the gear wheel, and whose stem is united with a handle 5^a. The handle and stem are hollow or bored lengthwise to receive a plunger rod 6, and there is pivoted in the bifurcated part of the lever an operating pawl 7 to the outer arm of which said plunger rod is pivotally connected. The inner arm of the pawl terminates in a tooth of appropriate form to engage the teeth of the gear wheel 4. In an enlargement of the bore of the handle 5^a a spring 8 surrounds the plunger rod bearing at the inner end against a washer 9, which rests upon a shoulder of the handle at the inner end of the enlarged portion of the bore, and at its outer end said spring bears against a shoulder formed by an enlargement of the plunger rod. The latter terminates in a thumb knob 6^a.

The gripping devices which will presently be described, are mounted respectively upon the short leg of the L-shaped base and upon an extension or arm 3^a of the slide block. It will be obvious that throwing the lever over to the left from the position shown in Figs. 2 and 3 with the pawl 7 in engagement with the gear wheel will result in turning the latter with the lever and causing it to travel to the left along the rack carrying the slide block with it. Thus the gripping device on the slide block is moved toward the gripping device on the base. It sometimes will take several strokes of the lever to do the work, and furthermore the operator will be required to let go the lever and apply himself to the job of sealing the strap ends or nailing the strap to the box while it is held stretched by the tool, and consequently a holding pawl is required to prevent backward movement of the slide block. The holding pawl as here shown and desig-

nated 10, is pivoted upon the axis of the gear wheel 4 between the latter and an offset portion of one tine of the bifurcated end of the operating lever, said pawl extending 5 out over the rear end of the slide block 3 and having its tooth 10^a offset so as to engage the rack 2^a. The pawl maintains its engagement therewith by gravity, and it will be obvious that as the slide is worked along the rack the 10 tooth of the pawl will ride over the teeth of the rack and be ready at all times to prevent backward movement of the rack.

When the requisite degree of stretching of the strap has been accomplished and the 15 strap has been nailed to the box or its ends sealed together, the said pawl must of course be disengaged from the rack, and in order to provide for expeditiously sliding the block back again, it is desirable to also disengage the operating pawl 7 from the gear wheel. 20 The latter thing may be done by applying pressure upon the thumb knob 6^a, and the disengagement of the holding pawl may be accomplished by throwing the lever to an 25 extreme position, as illustrated in Fig. 4. Thus the operator while grasping the handle of the lever may press with his thumb upon said knob and disengage the operating pawl from the gear wheel and may at the 30 same time throw the lever to extreme position and thereby lift the holding pawl out of the rack. For the purpose of effecting the latter result the before-mentioned offset tine of the bifurcated end of the lever is 35 formed with a radial lug 5^a to act upon a lateral lug 10^b formed upon the holding pawl.

There is fixedly mounted upon the end of the base beyond the rack a holding knob 11 40 whose stem stands at an outward angle. This knob may be conveniently secured to the base by a long machine screw, as shown by dotted lines in Fig. 2. The knob facilitates the handling of the tool, and particularly affords a convenient means by which 45 the operator can hold the tool down on the box and obtain the needed purchase when working the lever in the application of power to stretch the strap.

50 Passing now to the gripping devices, there is formed upon the upper side of the short leg of the L-shaped base an inclined boss 2^b, and a similar boss 3^b is formed upon the upper side of the arm 3^a of the slide which 55 was before mentioned. These bosses overhang the ends of their respective members and the latter carry insets of hard metal 12 and 13 respectively, which have projecting portions 12^c and 13^c underlying the bosses, 60 and constituting strap rests.

Inasmuch as each set of gripping devices has the same construction a detailed description of one will suffice for both. The inclined boss is screw-threaded for a distance from the top and then has a smooth

bore and an annular shoulder, and below that a bore of smaller diameter which opens through bottom of the boss. A grip plug 14 occupies this small bore and protrudes from the boss. It also extends up into the smooth bore of the larger diameter and is formed with an enlarged head 14^a. A coiled spring 15 surrounds the plug under that head and bears against the annular shoulder, and this spring normally holds the plug up so that 70 the strap *a* may be readily slipped in between the plug and the rest-piece 12^a. A knob 16 is provided with a screw-threaded stem 16^a engaging the screw-threaded portion of the bore of the boss and is rounded 75 on its inner end to engage the flat top of the head of the plug.

The inner or bottom end of the plug is of general conical form and made with a series of annular teeth 14^c which, in diametrical 80 section of the plug, will be seen to be of ratchet-like character, as shown most clearly in Figs. 6 and 7, the teeth pointing toward the apex of the cone.

The plug is free to turn in its bore whereby the wear upon its gripping teeth will be distributed around the circle of those teeth. Another effect will now be pointed out, which is due to a loose mounting of the plug in the bore that permits a slight rocking. 85 It will be observed that in Fig. 6 the plug is shown rocked or canting one way and in Fig. 7 the other. Fig. 6 illustrates the effect of screwing down the knob 16. Owing to the fact that this knob is inclined and the 90 plug is also inclined, making an acute angle with the incoming strap end, the forcing down of the plug upon the top surface of the strap will cause it to rock or cant, the teeth either slipping upon the strap slightly, 95 or else immediately taking hold and slightly shifting the strap. The condition is illustrated in Fig. 6 and the point to be observed is that this effect prepares for the 100 securing of a bull-dog grip upon the strap. 105 Thus when the operating lever is worked to advance the slide block with both gripping knobs screwed down, the result of the strain thereby put upon the strap through the medium of the gripping devices will be 110 to cause each grip plug to cant the other way and tighten its hold upon the strap, the teeth, owing to their ratchet-like character digging into the metal of the strap. This 115 effect is illustrated by Fig. 7. It will be 120 seen therefore that the strap ends will be held with the utmost tenacity, and so the operator, after working the lever to stretch the strap and get the strap ends overlapped, may safely let go and devote himself to the 125 job of nailing the strap to the box and applying the seal to the overlapping ends.

When all of this has been accomplished the grip knobs will of course be turned back, whereupon the springs 15 will lift the grip- 130

plugs away from the strap and the tool can then be readily taken away for use upon the next strap.

It should be noted that the metal insets 5 12 and 13 have vertical faces against which the strap-ends will be pushed when inserting them sidewise into the grips, and thus they serve to properly aline the strap ends. In the same connection it should be noted that any width of strap, such as used in this kind 10 of work, may be accommodated, and that no adjustment of grips to different widths is necessary, and further that no readjustment is required for different thicknesses or gages of stock, *i. e.*, no resetting or rearrangement. Furthermore each grip takes hold at one 15 place so there is no disfiguring or mutilation of the strap by engagement at numerous points or by doubling up or by multiplying 20 the gripping action. Overlapping of strap ends is not required in connection with the gripping action, and all that is necessary by way of any overlapping is that there be sufficient overlap for sealing purposes when 25 a seal is used. Hence the tool of the present invention makes for economy in amount of strap used.

We claim:

1. A strap-stretching tool comprising a 30 base having a rack, a slide, grips on the base and slide, a gear on the slide, a driving pawl engaging the gear, a holding pawl carried by the slide and engaging the rack, and an operating lever on the slide and carrying 35 the driving pawl and also carrying connections for disengaging said pawl from the gear, said connections operable from the handle-end of the lever, and said lever itself adapted by excess movement to disengage 40 the holding pawl from the rack.

2. A strap-stretching tool comprising a base having a rack, a slide, grips on the base and slide, an operating lever, a driving pawl pivotally mounted thereon and engaging the 45 gear, a plunger rod connected to said pawl and extending to the handle-end of the lever, and a holding pawl carried by the slide and engaging the rack and disengageable therefrom by the operating lever.

50 3. A strap-stretching tool comprising a base having a rack, a slide, grips on the base and slide, a gear on the slide, means for operating the gear, and a holding pawl concentric with the gear and engaging the rack, and displaceable by said means.

4. A strap-stretching tool comprising a base having a rack, a slide, grips on the base and slide; a gear on the slide, an operating lever concentric with the gear, and a holding pawl concentric with the gear and engaging the rack and engageable by the lever for disengagement from the rack.

5. A strap-stretching tool comprising a base having a rack, a slide, grips on the base and slide, a gear on the slide, an operating

lever concentric with the gear, a driving pawl on said lever and engaging the gear, and a holding pawl concentric with the gear and engaging the rack; the lever and said holding pawl having coacting lugs, substantially as and for the purpose described. 70

6. A strap-stretching tool comprising an L-shaped base, a slide block on the longer leg thereof and having a lateral arm confronting the shorter leg, said arm and leg carrying strap-rests, gripping devices on said arm and leg and overhanging said rests with open spaces between for lateral ingress and egress of strap, and means located to one side of said devices for driving the slide 80 block. 75

7. A strap-stretching tool comprising an L-shaped base having a rack on the upper side of its longer leg, a slide-block fitted to said leg and having a lateral arm confronting the shorter leg of the base, said arm and leg carrying alined strap rests, gripping devices on said arm and leg and overhanging said rests with open spaces between for lateral ingress and egress of strap, and 90 means applied to said rack for driving the slide-block. 85

8. A strap-stretching tool comprising an L-shaped base having a rack on the upper side of its longer leg, a slide-block fitted to 95 said leg and bridging the rack and having a lateral arm confronting the shorter leg of the base, said arm and leg carrying alined strap rests, gripping devices on said arm and leg and overhanging said rests with 100 open spaces between for lateral ingress and egress of strap, and means applied to said rack for driving the slide block. 100

9. In a strap-stretching tool, a grip comprising a rest, an overhanging boss with an oblique bore, a grip plug loose in the bore and having a ratcheted acting end, and means operating upon the grip-plug to force it angularly into engagement with the strap. 105

10. In a strap-stretching tool, a grip comprising a rest, an overhanging boss with an oblique bore, a grip-plug loose in the bore and having a ratcheted acting end, and means operating upon the grip-plug to force it angularly into engagement with the strap 110 canting it as permitted by the loose mounting in the bore, said grip-plug adapted to rock back under strap strain and thereby tighten its hold on the strap. 115

11. In a strap-stretching tool, a grip comprising a rest, an overhanging boss with an oblique bore, a grip-plug loose in the bore and having a conical end with a series of encircling teeth, and means operating upon the grip-plug to force it angularly into engagement with the strap. 120

12. In a strap-stretching tool, a grip comprising a rest, an overhanging boss with an oblique bore, a grip-plug loose in the bore and having a ratcheted acting end, and a 130

screw in the boss operating upon the grip-plug to force it angularly into engagement with the strap.

13. In a strap-stretching tool, a grip comprising a rest, an overhanging boss with an oblique bore of varying diameter and screw-threaded for a distance from one end, a grip-plug occupying a smaller diameter portion of the bore at the other end and protruding through the same and terminating in a conical ratcheted acting portion, said

plug loosely fitting the bore, a spring engaging under the head of the plug to retract it, and a knob with a screw stem engaging the threaded portion of the bore and having a rounded end to act upon the grip-plug.

14. A grip plug for strap-stretchers having a conical-acting end with annular ratchet teeth pointing toward the apex of the cone.

RALPH H. NORTON.
